(57) **CLAIM**

The ornamental design for cabinet, as shown and described.

DESCRIPTION

FIG. 1 is a perspective view of a cabinet in a horizontal orientation showing our new design;

FIG. 2 is a rear view of the cabinet illustrated in FIG. 1;
FIG. 3 is front view of the cabinet illustrated in FIG. 1;
FIG. 4 is a left side of the cabinet illustrated in FIG. 1;
FIG. 5 is a right side view of the cabinet illustrated in FIG. 1;

FIG. 6 is a top view of the cabinet illustrated in FIG. 1;
FIG. 7 is a bottom view of the cabinet illustrated in FIG. 1;
FIG. 8 is a perspective view of the cabinet illustrated in FIG. 1;

FIG. 9 is a cross-sectional view of the cabinet illustrated in FIG. 2;

FIG. 10 is a cross-sectional view of the cabinet illustrated in FIG. 3;

FIG. 11 is a cross-sectional view of the cabinet illustrated in FIG. 2; and,

FIG. 12 is a cross-sectional view of the cabinet illustrated in FIG. 6.

The broken lines shown in the drawings show portions of the design that form no part of the claimed design.

1 Claim, 7 Drawing Sheets
